(57) **CLAIM**

The ornamental design for a steel tongue drum, as shown and described.

DESCRIPTION

FIG. 1 is a front, right and bottom perspective view of a steel tongue drum showing my new design;
FIG. 2 is a rear, left and top perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan view thereof;
FIG. 9 is an enlarged view of the portion taken at line-9 in FIG. 1;
FIG. 10 is an enlarged view of the portion taken at line-10 in FIG. 1;
FIG. 11 is an enlarged view of the portion taken at line-11 in FIG. 5;
FIG. 12 is an enlarged view of the portion taken at line-12 in FIG. 7; and,
FIG. 13 is an enlarged view of the portion taken at line-13 in FIG. 8.

The broken lines in the figures illustrate portions of the steel tongue drum that form no part of the claimed design. The dot-dash broken lines represent boundaries of the enlarged portions and form no part of the claimed design.
